LEAD-WOOL AND GROUND-CORK PACKING

Application filed May 10, 1928. Serial No. 276,768.

Our invention relates to packing for pistons, piston rods, stuffing boxes, or the like.

In accordance with our invention, we provide a packing having a body portion formed of lead wool. This lead wool is made up of fine strands of lead, varying considerably in length. The strands of lead have about the cross sectional area of a coarse strand of human hair, more or less. The strands of the lead forming the lead wool are arranged generally longitudinally, but the strands are somewhat matted. The lead wool serves to fill in irregularities or rough places in the moving contacting part, thus producing a smooth contact surface. By virtue of having the lead in fine strands, the lead wool mass possesses some degree of resiliency and will not readily pack or cold weld, into a solid mass. The body of lead wool has arranged therein or distributed therethrough, a mixture of finely ground or granular cork, impregnated with finely ground graphite and oil. The graphite serves as a lubricating medium, and the ground cork produces an expandible medium distributed throughout the body of the lead wool, and this ground cork will cause the entire packing to possess proper resiliency, particularly when the cork is acted upon by moisture and pressure, whereby the packing will automatically expand to compensate for wear.

In the accompanying drawings, forming a part of this specification and in which like numerals are employed to designate like parts throughout the same,

Figure 1 is a plan view of a strip of lead wool included in the packing,

Figure 2 is an edge elevation of the strip of lead wool with the cork and graphite layer arranged thereon,

Figure 3 shows the strip of lead wool twisted to produce the packing strip, and,

Figure 4 shows the packing strip bent into annular packing.

In the drawings, wherein for the purpose of illustration, is shown a preferred embodiment of our invention, the numeral 10 designates a strip of lead wool. This lead wool is made up of fine strands of lead, having about the cross sectional area of a strand of coarse

human hair, although this cross sectional area may vary somewhat. The finer the strands are, the more satisfactory are the results, since the lead wool mass will then possess some degree of resiliency, and will not crush or cold weld into a solid mass. The strands of lead wool vary in length and some of them extend throughout the entire length of the strip. These strands are also somewhat matted. These granular or finely ground cork, with the finely ground graphite, are first soaked in hot lubricating oil, and the mixture is then sprinkled upon the strip of lead wool producing a layer 11, as shown. The next step in producing the packing is to spirally twist the strip of lead wool with the layer of ground cork and graphite upon itself. This twisting action serves to distribute the ground cork and graphite throughout the entire mass of the packing.

While the ground cork and graphite is arranged generally in a spiral layer, in the finished product, yet a considerable amount of the same becomes distributed throughout the entire mass of the lead wool particularly when the packing is being used. The packing strip produced in Figure 3, by the spiral twisting, is now bent into an annular packing as shown in Figure 4.

When the packing is used in a stuffing box, to surround a piston rod, for example, the lead wool being soft, is readily cut by irregularities or rough portions of the piston rod, and will fill these irregularities or rough places, producing a smooth surface. The graphite, being distributed with the cork, to a considerable extent, throughout the entire mass of the lead wool, works through the same, due to the action of the piston rod or other movable part and affords lubrication. The cork saturated with the oil, retains its resiliency, and lends expansibility to the packing, which with the fine strands of the lead wool, produce a packing having some degree of resiliency. When the ground cork is acted upon by steam or moisture, it expands, causing the packing to expand, for effecting a tight joint.

It is to be understood that the form of our invention, herewith shown and described, is

to be taken as a preferred example of the same, and that various changes may be resorted to in the formation of the constituents of the packing, and the manner in which they are combined, without departing from the spirit of our invention, or the scope of the subjoined claims.

Having thus described our invention, we claim:—

10 1. A packing for a piston rod or the like, comprising a body portion of lead wool formed of fine strands of lead, and finely divided cork embedded within said lead wool body portion and adapted to expand and im-
15 part to the lead wool body portion a suitable resiliency.

20 2. A packing for a piston rod or the like, comprising a body portion of lead wool formed of fine strands of lead having voids between the same, and granular cork embedded within said lead wool body portion, the grains of cork being arranged within the voids between the strands of the lead wool and such grains being distributed throughout
25 substantially the entire mass of said body portion, said grains of cork being adapted to expand and to impart to the body portion throughout its mass a suitable resiliency.

30 3. A packing for a piston rod or the like, comprising a body portion of lead wool formed of strands of lead having voids between the same, and oil impregnated granular cork embedded within the lead wool body portion, the grains of cork being arranged
35 within the voids between the strands of the lead wool, said grains of cork being adapted to expand and to impart to the body portion a suitable resiliency.

In testimony whereof we affix our signatures.

GREGORY E. SAWYER.
JOHN W. SMITH.
